LINK FOR VENETIAN BLINDS

Marshall Laird, Los Angeles, Calif.

Application November 4, 1940, Serial No. 364,176

7 Claims.

(Cl. 156—17)

My invention has to do with Venetian blinds and, more particularly, it relates to links for interconnecting the slats of the blind in a manner to eliminate the use of conventional ladder tape.

A notorious objection to Venetian blinds of conventional construction is that the fabric ladder tape used to collapsibly space the slats apart quickly becomes soiled or worn and must be frequently cleaned, repaired or replaced. While attempts have been made to provide metal hinged links to substitute for fabric tape ladders, those attempts heretofore have been unsuccessful for several reasons. For instance, the provision for the types of hinge connections that have been attempted have rendered the links too thick or bulky to enable efficient and neat collapse of the blind and also such hinge connections have been of a type which would stick or bind or would not break uniformly when the operating cord of the blind is moved to collapse the blind.

It is therefore among the principal objects of my invention to produce a hinged link, a plurality of which may be connected together and substituted for the conventional ladder tape; which will provide a ladder capable of as long a life as that of the slats themselves; which is extremely durable, economical and attractive; which may be easily assembled and disassembled; which provides maximum ease and uniformity of operation; which is not thick or bulky enough to interfere with neat, efficient and compact collapse of the blind; which will at all times break uniformly in the desired direction and manner; and which will not stick or bind.

How these and other objects and accomplishments of my invention are achieved will become apparent from the following detailed description of one presently preferred adaptation thereof, for which purpose I make reference to the accompanying drawing, in which:

Fig. 1 is an end view of a Venetian blind embodying my invention;

Fig. 2 is a fragmentary front view;

Fig. 3 is an end view showing the Venetian blind in collapsed position;

Fig. 4 is a front view of the upper portion of one of my improved ladder links;

Fig. 5 is a front view of the lower portion of one of said ladder links;

Fig. 6 is a cross-section taken on line 6—6 of Fig. 5, showing the ear portions bent out of the plane of the plate;

Fig. 7 is an end view of Fig. 4; and

Fig. 8 is an end view of Fig. 5.

Referring now to the drawing, I show a portion of a Venetian blind having the usual plurality of parallel slats 5, top and bottom bars 6, 7, respectively, and operating cord 8, all of well-known form and structure.

My improved collapsible ladder for supporting and interconnecting the slats of a blind is generally designated by the numeral 10 and is comprised of a lower section 15, an upper section 16 and a hinge pin 18.

As will be best seen from Figs. 5 and 8, the lower section 15 is a thin, flexible plate preferably composed of sheet metal, although it will of course be understood that other suitable materials may be used. The plate 15 has on its opposite side edges, adjacent the top edge, two pairs of oppositely disposed ears 21, 22, said pairs of ears being spaced apart a distance slightly greater than the thickness of the upper section 16. The plate 15 also has a central cutaway portion 23 in its top and the bottom edge of the plate is backwardly curved to provide a socket portion 24 to receive a hinge pin 18.

The upper section 16 is comprised of a plate preferably of the same thickness and material as that of the lower section 15 and has a body portion presenting a downwardly opening recess 31. The upper edge of the plate is backwardly curved to provide spaced hinge pin receiving sockets 32, spaced apart a distance substantially equal to the width of socket 24 of the lower plate, which latter socket fits into the space between sockets 32 and in alinement therewith. At opposite sides of the cutaway portion 31, I provide a pair of oppositely disposed slots 33 whose outer ends 34 are disposed diagonally upwardly and outwardly.

In mounting the device on a blind, I provide a mounting plate 40 which preferably is a thin, flexible metal strip bent upon itself to provide a round hinge pin receiving socket 41. Plate 40 is screwed or otherwise suitably secured to the top bar 6 and the upper section 16 of one of the ladder links is pivotally secured to the plate 40 by a hinge pin 18 passing through sockets 32, 41. Said hinge pin 18 also passes through a looped end 50a of a ladder bar 50 upon which the slat rests, the opposite end of said bar 50 being likewise mounted on the hinge pin 18 of another ladder link element 10 at the opposite edge of the slat. For the purpose of accommodating the width of the ladder bar, one of the top corner portions of the socket 32 is cutaway as shown at 32a. This cutaway portion 32a, as well as the respective ladder bars 50, are alternately placed to the right and left of the top section 16 of respective units 10—that is, for instance, the top-most ladder bar 50 may be on the left hand side of the front top link section 16 and, with respect to the next adjacent link unit 10 below, the ladder bar 50 will be on the right hand side, etc.

Next, as shown in Fig. 6 for the purpose of assembly, the opposite ears 21 of the lower section 15 are bent so as to be disposed at the same angle as that of the slot ends 34, so that the slots will pass the ears 21 and enable the upper

section 16 to rest between ears 21, 22. After the upper end of the lower section is thus inserted in slots 33, the ears 21 are then re-bent down to their normal position in a plane with the body portion of the lower section. This provides a hinged connection between the two link sections, the connecting ends of the link sections being slightly inwardly disposed towards the opposite side of the slat (see Fig. 1) so that when the operating cord is operated to collapse the blind, the links will always break uniformly inwardly.

Sufficient links are assembled in like manner to complete the blind to the desired length, a slat resting on each of the ladder bars, and each succeeding plate being pivotally secured to the lower section of the last installed link by means of another hinge pin 18 and another ladder bar 50. It will be understood of course that it requires a pair of oppositely disposed ladder links 10 at least for each end of the blind, although where unusually long slats are used there may be required one or more intermediate rows of ladder links 10. The lowermost link sections are pivotally connected to the bottom bar 7 by means of mounting plates 40 in the manner before described.

Preferably, one end of each of the hinge pins 18 is flattened at 18a to prevent longitudinal escape therefrom of the ladder bar. While the pins 18 are usually held in position by the weight of the elements below, I provide a positive means for holding those pins against longitudinal escape in a direction towards the flattened end, comprised of a short screwthread 60 on one end of the pin and a cooperating ear 61 struck out of the material of the socket portion 32, which ear is engaged by said thread when the pin is inserted and turned slightly. For the purpose of turning the hinge pin, I preferably provide a hole 63 in one end thereof, into which a small pin or like object may be inserted to turn the hinge pin.

While I have resorted to considerable detail for the purpose of making my invention understood, I wish it understood that within the broader scope of my invention, as defined by the appended claims, various modifications and adaptations may be made without departing from the spirit of the invention.

I claim:

1. A Venetian blind comprising parallel slats supported by hinged links disposed at opposite side edges of the slats, each of said links being hingedly connected to an adjacent link and comprised of an upper and a lower thin, flexible plate, one of said plates having therethrough a narrow elongated transverse slot whose opposite end portions are disposed at an angle to the intermediate slot portion and the other of said plates having an end portion inserted through said slot and opposite side projections which are bendable into the plane of the said end portions of the slot to permit passage therethrough and bendable into the plane of the intermediate slot portion to prevent escape from the slot.

2. A ladder for the slats of a Venetian blind or the like comprising a plurality of links, each comprised of: an upper and a lower plate, means for hingedly connecting the upper part of said lower plate to the lower part of said upper plate including a transverse slot in the upper plate into which projects the upper portion of the lower plate, the opposite ends of said slot being upwardly and outwardly disposed and pairs of vertically spaced ears on each side of each lower

plate, the topmost pair of ears being bendable into the plane of said end portions of the slot to permit insertion therethrough and bendable from that plane to hold said plates in assembly, 5 means for hingedly connecting each of said links to an adjacent link, and means associated with said last-named means for supporting the respective slats.

3. A hinged link of the class described comprising an upper and a lower plate of thin, flexible metal or the like, means for hingedly connecting said plates together comprising a transverse slot in one of the plates, the respective ends of said slot being disposed at an angle to the adjacent portion of the slot, a pair of vertically spaced ears on each of the opposite sides of the upper portion of the other plate, one pair of said ears being inserted through said slot and bent out of the plane of the end portions of the 15 slot to prevent longitudinal escape therefrom.

4. A ladder for the slats of a Venetian blind or the like comprising a plurality of links, each comprised of: an upper and a lower plate, means for hingedly connecting the upper part of said lower plate to the lower part of said upper plate, and means for hingedly connecting each link to an adjacent link including a backwardly bent portion of each plate whereby to provide a socket at each end of each link, an ear struck out of one 25 of said backwardly bent portions and projecting into one of said sockets and a hinge pin extending transversely through said sockets, said pin having a screwthread cooperating with said ear whereby to prevent longitudinal escape 30 of the pin.

5. An articulated ladder for the slats of a Venetian blind or the like comprising pairs of links, each link of each pair having one end portion pivotally connected to an adjacent slat and a plane-surfaced portion at and adjacent its other end, one of the links of each pair having a transverse slot spaced from its ends and extending through its plane-surfaced portion and the other link of each pair having its plane-surfaced portion projecting through said slot 35 whereby to hingedly interconnect said links.

6. An articulated ladder for Venetian blinds or the like comprising pairs of links disposed in rows at opposite edges of the slats, each link of each pair having one end portion pivotally connected to a link of an adjacent pair and a plane-surfaced portion at and adjacent its other end, one of the links of each pair having, through its plane-surfaced portion and spaced from its 40 ends, an elongated transverse slot and the other link of each pair having its plane-surfaced portion extending through said slot whereby to hingedly interconnect said links.

7. An articulated ladder for Venetian blinds or the like comprising pairs of links disposed in rows at opposite edges of the slats, each link of each pair having one end portion pivotally connected to a link of an adjacent pair and a plane-surfaced portion at and adjacent its other end, one of the links of each pair having, through its plane-surfaced portion and spaced from its ends, an elongated transverse slot, said slot having each of its end portions disposed at an angle to 55 its intermediate portion, and the other link of each pair having its plane-surfaced portion extending through said slot and having deformable ears for preventing longitudinal escape from the slot.
